CLAIM

The ornamental design for a nasal dilator, as shown and described.

DESCRIPTION

FIG. 1 is a perspective view of a nasal dilator showing another one of our new designs;

FIG. 2 is an enlarged view of the left side of the nasal dilator shown in FIG. 1 taken along line 2;

FIG. 3 is an enlarged view of the right side of the nasal dilator shown in FIG. 1 taken along line 3;

FIG. 4 is a front view of the nasal dilator shown in FIG. 1; FIG. 5 is an enlarged view of the left side of the nasal dilator shown in FIG. 4 taken along line 5;

FIG. 6 is an enlarged view of the right side of the nasal dilator shown in FIG. 4 taken along line 6;

FIG. 7 is a back view of the nasal dilator shown in FIG. 1; FIG. 8 is an enlarged view of the left side of the nasal dilator shown in FIG. 7 taken along line 8;

FIG. 9 is an enlarged view of the right side of the nasal dilator shown in FIG. 7 taken along line 9;

FIG. 10 is a top view of the nasal dilator shown in FIG. 1; FIG. 11 is an enlarged view of the left side of the nasal dilator shown in FIG. 10 taken along line 11;

FIG. 12 is an enlarged view of the right side of the nasal dilator shown in FIG. 10 taken along line 12;

FIG. 13 is an enlarged end view of the right side of the nasal dilator shown in FIG. 1; (Continued)

FIG. 14 is an enlarged end view of the left side of the nasal dilator shown in FIG. 1;
 FIG. 15 is a perspective view of a nasal dilator showing another one of our new designs;
 FIG. 16 is an enlarged view of the left side of the nasal dilator shown in FIG. 15 taken along line 16;
 FIG. 17 is an enlarged view of the right side of the nasal dilator shown in FIG. 15 taken along line 17;
 FIG. 18 is a front view of the nasal dilator shown in FIG. 15;
 FIG. 19 is an enlarged view of the left side of the nasal dilator shown in FIG. 18 taken along line 19;
 FIG. 20 is an enlarged view of the right side of the nasal dilator shown in FIG. 18 taken along line 20;
 FIG. 21 is a back view of the nasal dilator shown in FIG. 15;
 FIG. 22 is an enlarged view of the left side of the nasal dilator shown in FIG. 21 taken along line 22;
 FIG. 23 is an enlarged view of the right side of the nasal dilator shown in FIG. 21 taken along line 23;
 FIG. 24 is a top view of the nasal dilator shown in FIG. 15;
 FIG. 25 is an enlarged view of the left side of the nasal dilator shown in FIG. 24 taken along line 25;
 FIG. 26 is an enlarged view of the right side of the nasal dilator shown in FIG. 24 taken along line 26;
 FIG. 27 is an enlarged end view of the right side of the nasal dilator shown in FIG. 15;
 FIG. 28 is an enlarged end view of the left side of the nasal dilator shown in FIG. 15;
 FIG. 29 is a perspective view of a nasal dilator showing another one of our new designs;
 FIG. 30 is an enlarged view of the left side of the nasal dilator shown in FIG. 29 taken along line 102;
 FIG. 31 is an enlarged view of the right side of the nasal dilator shown in FIG. 29 taken along line 103;
 FIG. 32 is a front view of the nasal dilator shown in FIG. 29;
 FIG. 33 is an enlarged view of the left side of the nasal dilator shown in FIG. 32 taken along line 105;
 FIG. 34 is an enlarged view of the right side of the nasal dilator shown in FIG. 32 taken along line 106;
 FIG. 35 is a back view of the nasal dilator shown in FIG. 29;
 FIG. 36 is an enlarged view of the left side of the nasal dilator shown in FIG. 35 taken along line 108;
 FIG. 37 is an enlarged view of the right side of the nasal dilator shown in FIG. 35 taken along line 109;
 FIG. 38 is a top view of the nasal dilator shown in FIG. 29;
 FIG. 39 is an enlarged view of the left side of the nasal dilator shown in FIG. 38 taken along line 111;
 FIG. 40 is an enlarged view of the right side of the nasal dilator shown in FIG. 38 taken along line 112;
 FIG. 41 is an enlarged end view of the right side of the nasal dilator shown in FIG. 29;
 FIG. 42 is an enlarged end view of the left side of the nasal dilator shown in FIG. 29;
 FIG. 43 is a cross-sectional view of the left side of the nasal dilator shown in FIG. 30 taken along line 115; and,

FIG. 44 is a cross-sectional view of the right side of the nasal dilator shown in FIG. 31 taken along line 116.
